2 SHEETS—SHEET 2.

UNITED STATES PATENT OFFICE.

JOSEPH T. SCHLACKS, OF DETROIT, MICHIGAN.

RADIATOR.

1,209,044.

Specification of Letters Patent. Patented Dec. 19, 1916.

Application filed December 10, 1913. Serial No. 805,704.

To all whom it may concern:

Be it known that I, JOSEPH T. SCHLACKS, a citizen of the United States, residing at Detroit, in the county of Wayne and State 5 of Michigan, have invented certain new and useful Improvements in Radiators; and I do hereby declare the following to be a full, clear, and exact description of the invention, such as will enable others skilled in the art 10 to which it appertains to make and use the same.

Generally stated, my invention is directed to the improvement of radiators, but more particularly, has for its object the improvement 15 of that type of radiator extensively used in connection with automobiles and known as the cellular type of radiator. It is the common practice to make these cellular radiators of thin sheets of brass or copper, bent each to form a multiplicity of alternated relatively narrow and wide angular 20 plaits or corrugations. These plaits, when assembled in the completed radiator, give the same a rectangular cellular appearance 25 and form longitudinal air passages and intervening vertical water conduits having laterally projecting water spaces.

My improved radiator, in its preferred 30 form, is illustrated in the accompanying drawings wherein like characters indicate like parts throughout the several views.

Referring to the drawings: Figure 1 is a perspective view showing the complete radiator core or cellular body; Fig. 2 is a fragmentary horizontal section taken approximately on the line x^2-x^2 on Fig. 1; Figs. 3 and 4 are views in end elevation showing two of the so-called units of the radiator, portions of the unit shown in Fig. 3 being 35 broken away; Fig. 5 is a perspective of the unit shown in Fig. 4 with one plaited side thereof broken away; and Fig. 6 is a detail in horizontal section showing the radiator core unit illustrated in Fig. 4 on an exaggerated scale, and particularly illustrating the manner in which the ends of the plaited sheets of the units are preferably united, some parts being broken away.

This improved radiator is made up of a 40 multiplicity of so-called units, to-wit, of an appropriate number of units such as shown

in Fig. 3, combined with an appropriate number of units, such as shown in Fig. 4. The shells of these so-called units are made up of thin metal sheets 1, preferably of brass, which are bent to form approximately rectangular relatively narrow plaits 2 and intervening relatively wide air passages 3. In the present construction, both of the plaited side walls, as well as the top and bottom walls of the radiator unit, are made from a single or continuous strip of sheet metal. The radiator unit constructed as shown in Fig. 4, has horizontal upper and lower walls 1^a thus formed, whereas the radiator unit such as shown in Fig. 3 has oblique top and bottom or corner forming walls 1^b formed in the manner indicated. Here it may be stated that, advisably, these corrugated sheets are made in long strips or 45 ribbons and are cut into proper lengths, and the flattened end portions 1^a and 1^b are formed by straightening out certain of the plaits 2. The ends of the said sheets 1 are then preferably overlapped and interlocked, 50 as shown in Fig. 6, thereby forming complete or endless corrugated sheets in which the inwardly projecting plaits 2 are horizontally aligned but slightly spaced apart. In Fig. 6, however, the overlapped and interlocked ends of the sheet 1 are, for clearness, 55 shown as slightly separated, whereas in practice, they will be as closely united as possible.

Between the front and rear end portions 60 of the horizontally aligned plaits 2, are interposed flat and very rigid metal parting and reinforcing strips 4 that extend from the bottom to the top walls 1^a or 1^b, as the case 65 may be, of the radiator unit in which they are applied. These combined parting and 70 reinforcing strips space apart the adjacent intermediate portions of the horizontally aligned plaits 2 and form air passages 5 that connect the horizontal air passages 3, so that 75 air can circulate vertically in, as well as horizontally through the radiator unit. Otherwise stated, the air passages 5 afford 80 vertical communication between the horizontal air passages 3 of the radiator. The 85 parting strips 4, for an important purpose 90 hereinafter to be fully stated, project pref-

erably both at front and rear, beyond the front and rear faces of the radiator core, that is, beyond the front and rear edges of the soft metal sheets 1. These parting strips 5 are preferably made of steel.

The front and rear edges of the plaits 2 are pressed together, as shown, at 2^a, and the vertical edges of the said sheets 1, between the ends 2^a of the plaits 2 are offset or 10 pressed outward, as shown at 2^b, so that when a number of units are placed together, as shown in Figs. 1 and 2, the intermediately adjacent and connected sheets will be spaced apart and will form water tubes having vertical water conduits 6 with horizontally 15 aligned laterally offset water spaces formed within the oppositely projecting plaits 2 of the adjacent units. The radiator elements, when properly assembled, make a cellular 20 radiator core that is octagonal. Otherwise stated, they make a core that would otherwise be rectangular but has beveled corners. Hitherto, it has been customary in making cellular radiators, to first make the core 25 rectangular and then to saw off the corners. That operation requires subsequent resoldering of all of the numerous joints cut through in sawing off the corners of the core, and this, obviously, is a slow and expensive 30 operation, which, when completed, does not give a finished or satisfactory job. My improved manner of forming the beveled corner forming ends on certain of the outside units of the radiator core gives a finished 35 units and completely satisfactory job at a minimum of cost. The units of the radiator, when properly assembled in suitable form, have their joints closed at the front and rear edges 2^b of the corrugations 2, and parting 40 strips 4 are rigidly united to the ends of the said corrugations 2, by subjecting the same to a solder bath. The parting and reinforcing strips 4 perform several important 45 functions, to-wit, they very greatly reinforce the radiator core. When used in connection with the plaited metal sheets, they serve to space the plaits thereof, to afford vertical communication between the horizontal air passages; and when projected at 50 their edges beyond the face of the radiator, or beyond the vertical edges of the relatively thin and pliable metal sheets, they afford a guard adapted to receive impacts and to protect the edges of the plaited, or otherwise 55 formed relatively soft sheets, from being distorted or bent out of shape. Radiators of this character when applied in automobiles, are, as is well known, exposed at the front of the machine where they receive the 60 brunt of almost all head-end collisions or impacts, and as the pliable sheets of the core are very easily distorted, these radiators are very frequently distorted and the radiators seriously damaged even by compara-

tively light impacts. In fact, a very large 65 amount of repair work on these cellular radiators is made necessary from these causes. The parting and reinforcing strips are, of course, of much thicker metal than the plaited sheets of the radiator core, and when 70 the said strips are made of steel, they make the radiator core very rigid. Of course, the projection of the parting strips at the front face of the radiator core is more important than at the rear, but there is an advantage 75 in projecting both in front and at the rear, because the frail soft metal sheets of the core are very liable to be damaged, by breaking of the frame or even by workmen making 80 repairs or working around the radiator.

The complex horizontal and vertical circulation of air between the elements of the radiator, and the large amount of radiating surface exposed to the air thus circulated, resulting from the formation of the water 85 conducting tubes, gives a radiator an exceedingly high heat radiating and cooling efficiency. It will, of course, be understood that in practice, the upper extremities of the water conduits or conducting tubes will 90 be in communication with an upper water head or tank, whereas, the lower extremities of said conduits or tubes will be in communication with a lower water head or tank, which water heads or tanks are connected to 95 the water jacket of the explosive engine of the automobile, by means of suitable water circulating tubes.

The improved radiator, while particularly designed and especially adapted for use in 100 connection with automobiles, is, as will be understood, capable of general use wherever a radiator of this general character may be found serviceable.

What I claim is:

1. A radiator made up of a plurality of units, each unit comprising a continuous plaited metal sheet bent to form the sides, top and bottom walls of the unit and having its plaits assembled to form water conduits 110 and intervening air spaces, and with the plaits of one unit arranged opposite the plaits of the other unit, and flat sheet metal combined parting and reinforcing strips secured at the front and rear walls of the 115 units between the opposed plaits, and spacing the intermediate portions of the plaits of adjacent units.

2. A radiator made up of a plurality of units, each unit comprising a continuous 120 plaited metal sheet bent to form the sides, top and bottom walls of the unit and having its plaits assembled to form water conduits and intervening air spaces, and with the plaits of one unit arranged opposite the 125 plaits of the other unit, and flat sheet metal combined parting and reinforcing strips secured at the front and rear walls of the

units between the opposed plait, and spacing the intermediate portions of the plait of adjacent units, the said parting and reinforcing strips projecting beyond the exposed front edges of the radiator units to receive impacts and protect said units from distortion.

In testimony whereof I affix my signature in presence of two witnesses.

JOSEPH T. SCHLACKS.
